UNITED STATES PATENT OFFICE.

CHASE M. BROUSE, OF MITCHELL, SOUTH DAKOTA.

SNAP FASTENER.

Application filed August 10, 1925. Serial No. 49,303.

To all whom it may concern:

Be it known that I, CHASE M. BROUSE, a citizen of the United States, residing at Mitchell, in the county of Davison and State of South Dakota, have invented certain new and useful Improvements in a Snap Fastener, of which the following is a specification.

This invention relates to improvements in fastening devices, and is more particularly adapted to a fastener for use in attaching a feed bag to the bridle on the head of an animal.

One of the important objects of the present invention is to provide a fastener which is of such construction as to permit the feed bag to be readily attached or detached therefrom, and will further be prevented from becoming accidentally disengaged after it has been attached to the bridle, and more particularly to the cheek straps.

Another important object is to provide a device of the above mentioned character, wherein the fastener includes a snap member, the same being formed of a single strand of wire, and an attaching member also formed of a single strand of wire, and providing a means for attaching the strap members to the bridle.

A further object is to provide a fastener of the above mentioned character which is simple in construction, inexpensive, strong and durable, and further well adapted to the purpose for which it is designed.

Other objects and advantages of the invention will become apparent during the course of the following description taken in connection with the accompanying drawing.

In the accompanying drawing forming a part of this application and in which like numerals designate like parts throughout the same:

Figure 1 is a perspective view of my improved fastener showing the manner in which the same supports a feed bag on the bridle cheek strap.

Figure 2 is a side elevation of the fastener embodying my invention.

Figure 3 is a front elevation.

Figure 4 is a view similar to Figure 2, with the parts reversed, and

Figure 5 is a view of the strand of wire forming the snap fastener showing the same after the ends have been bent.

In the drawing, wherein for the purpose of illustration is shown the preferred em-

bodiment of my invention, the numeral 1 designates generally the snap fastener forming a part of the present invention, the same being formed of a single strand of wire 60 of spring steel. The elongated strand of wire has its respective ends bent back upon themselves as at 3 and 4 respectively, to provide the relatively short arm 5, and the relatively long arm 6. Both of the bends 65 3 and 4 are looped as clearly illustrated in Figure 5, and the purpose thereof will hereinafter be more fully described.

The intermediate portion 2 of the strand of wire has a coil 7 formed therein, the same 70 being located at a point adjacent the free ends of the arms 5 and 6. The free end of the arm 5 is bent back upon itself to provide a coil or loop 8 while the free end of the arm 6 is bent back upon itself to provide the coil 9, and is then twisted over the adjacent portion of the intermediate portion 2 of the wire as illustrated in the drawing. The coils or loops 7, 8, and 9 respectively are adapted for registration with 80 each other when the arm 5 is bent back upon the intermediate portion 2 of the wire at a point adjacent the coil 7.

The arm 6 is bent back upon itself intermediate its ends as at 10 so that the looped 85 ends 3 and 4 will be disposed in overlapping relation with respect to each other, and the bent portions of the arms will be arranged in parallel spaced relation with respect to the intermediate portion 2 of the 90 wire.

It is obvious that when an inward pressure is exerted on the arm 5, the looped portion 3 thereof will be moved away from the looped portion 4 of the arm 6 so that the 95 feed bag A may be placed over the looped end 4 of the arm 6, and disposed within the snap fastener, it being understood of course that the feed bag is provided with a suitable opening to permit the looped end of 100 the arm 6 to pass therethrough.

The snap fastener is attached to the cheek strap B of a bridle C, through the medium of the member designated generally by the numeral 11. The attached member 11 is 105 also formed of a single strand of spring steel wire, the intermediate portion thereof being looped as indicated at 12, and this looped portion extends through the registering coils or loops 7, 8, and 9 respectively of the snap fastener 1. The respective arms of the wire comprising the at-

taching member are then twisted as illustrated at 13, and are disposed laterally in opposite directions as indicated at 14, and 15 respectively. The arm 16 is then bent laterally as at 17, and in a similar manner, the other arm 18 is also disposed laterally as indicated at 19. The free end of the arm 16 is then bent inwardly as at 20 as is also the free end 21 of the arm 18. The abutting 10 free ends of the arms 16 and 18 are soldered together. In this manner, a substantially rectangular shaped loop is formed for co-operation with the cheek strap B in the manner clearly illustrated in Figure 1 so 15 that the member 11 will be carried by the cheek strap, and the snap member will be prevented from becoming accidentally disengaged therefrom.

A fastener of the above mentioned character may not only be used in connection with supporting a feed bag on a bridle, but may also be used wherever it is necessary to employ a snap fastener. The simplicity in which the present device is constructed 25 enables the same to be readily and easily opened or closed, and will furthermore be very inexpensive in its manufacture.

While I have shown the preferred embodiment of my invention it is to be understood that minor changes in the size, shape and arrangement of parts may be resorted to without departing from the spirit of the invention, and the scope of the appended 30 claims.

Having thus described the invention, what I claim as new and desire to secure by Letters Patent is:—

1. A snap fastener, formed of a single strand of spring steel wire, said strand of 40 wire having the end portions formed to extend in adjacent relation along the central portion to provide a relatively short arm, and a relatively long arm having loops formed at the free ends of the arms, the 45 short arm having the end portion to extend along the intermediate portion of the strand of wire adjacent the free end of the longer arm, the longer arm having the free end formed to extend toward the shorter arm 50 and adapted to cooperate with the end of said short arm to provide a closure.

2. A snap fastener, formed of a single

strand of resilient wire, said wire being formed to provide a long arm and a short arm with the end portions extending toward 55 and engaging the intermediate portion of the wire, the wire at the end portions of said arms being formed to provide loops, the end portions of the arms extending toward each other in spaced relation to the 60 central portion and having the loops at the ends in overlapped cooperation.

3. A snap fastener, formed of a single strand of resilient wire, said wire being formed to provide a short arm and a long 65 arm extending in opposite directions with the end portions of the wire positioned against the central portion to provide double strands in each arm, loops provided at the free ends of each arm, said arms being 70 formed with the free ends extending toward each other in spaced parallel relation to the central portion and overlying the central portion of the wire, the loops at the ends of the arms having overlapped cooperation, 75 and an attachment member associated with the snap fastener.

4. A fastener of the class described formed with a single strand of wire, said wire having the end portions extended in parallel 80 relation along the central portion, said wire being formed at the central portion to provide a coil, and the end portions of said arms extending toward each other in spaced parallel relation to the central portion and 85 having cooperative engagement to provide a closure.

5. A fastener of the class described, formed of a single strand of wire, the end portions of said wire engaging the intermediate portion, the terminal ends of the wire and the central portion being formed to provide a plurality of registering coils, the portions at each side of said coil forming a pair of arms, loops formed at the 95 free ends of said arms, and the free ends of said arms extending toward each other and overlying the central portion of the wire in spaced parallel relation, said loops having cooperative engagement to provide 100 a closure.

In testimony whereof I affix my signature.

CHASE M. BROUSE.
